LAMP SHADE STUD SUPPORT

Philip Miller, Flushing, N. Y.

Application June 27, 1951, Serial No. 233,737

4 Claims. (Cl. 240—148)

1

This invention relates to frames for lamp shades, and more specifically to the stud support for the same and still more particularly to a stud support which swivels on a wire frame or harp.

Known to me is the production of lamp shade frames or harps having a swiveling support for the stud to which the lamp shade is attached by a finial and involving a wire frame to which a lamp shade stud is affixed by a stud supporting head. In such construction the stud head end may be resorted to, to exert frictional contact upon the wire in opposition to a head supporting the same. The relationship of the material of the head to the wire and the ability to alter the tension by the screw threading of the stud frequently results in such loss of a predetermined frictional contact as gradually to destroy the usefulness of the stud mounting to provide a swiveling movement between the stud and the wire frame.

Accordingly, it is an object of my invention to provide a lamp shade frame having a round or trunnioning section to which a stud support may be attached by a head, the head having provision for supporting the stud independently of any friction which the head may exert upon the frame. In this manner, the material of the stud, its head or any portion thereof, and the use of the screw shank thereof will not subject the head and the frame engaging segments to alteration. Thus, long life for swiveling frictional engagement is assured and is effected with great economy in production of the associated parts.

Still more particularly it is an object of my invention to provide a lamp shade frame having a stud supported thereon for swiveling movement relatively to the frame by the provision of a stud supporting head of extremely simple form and low cost construction, which independently of the stud support or any part thereof may be adjusted in affixing the same to the wire, to provide in an extremely compact bearing section, inherent resiliency and surface contact for swiveling movement of the head with relation to the frame.

Still more particularly it is an object of this invention to provide a stud support characterized by a head having an undulating bearing surface in relation to which the opposed bearing head, walls, fingers, claws are stressed, to provide frictional engagement independently of the stud, whereby use of the finial on the stud in no way alters the frictional engagement and the material of the stud may be selected at random as well as to effect simplicity of assembly.

To attain these objects and such further objects as may appear herein or be hereinafter pointed out, I make reference to the accompany-

ing drawings, forming a part hereof, in which—

Figure 1 is a side elevation, partly in section, of a lamp showing my construction;

Figure 2 is a magnified fragmentary plan view 5 of a stud supporting head on the line 2—2 of Figure 1;

Figure 3 is a view similar to Figure 2, showing the lower side of the stud supporting head;

Figure 4 is an end elevation thereof;

10 Figure 5 is a section taken on the line 5—5 of Figure 4;

Figure 6 is a fragmentary plan view of another embodiment of my invention similar to Figure 2;

Figure 7 is a fragmentary section taken on the 15 line 7—7 of Figure 6;

Figure 8 is a fragmentary section taken on the line 8—8 of Figure 7.

Summarizing my invention, it involves the provision in a lamp construction having a wire frame harp or the like in which a round section supports a head providing a mount for a finial stud characterized by a head formed with undulating bearing surfaces, which surfaces are in opposed relation to the wire engaging segment 20 of the head in the form of integral ears, fingers, clamping members, claws, whereby the clamping members in the form as described are stressed in relation to the bearing members by the inherency of the bearing head and independently 25 of the stud or any portion thereof, such as the head or shank.

Making reference to the drawing, I show a lamp 10 having a bulb socket 11 from which a frame 12 is supported. The frame 12 spans a light bulb 13 positioned in the socket 11. The socket has a base 14 in which the fingers 15 of the frame are supported, either permanently or releasably. The frame 12 is preferably of wire having branches 16 and 17 outlining a segment 18. Where round stock wire is employed, the segment 18 provides a trunnion. Where the wire is made of flat stock, the segment 18 may be rounded, for purposes which will appear more clearly as this description proceeds.

In accordance with my invention, it is intended to provide for the lampshade frame 19 having the usual collar 20, a finial 21 for engagement of a stud 22. For this purpose I provide a stud supporting head 23. The head comprises a disk-shaped sheet of malleable metal having an axially shouldered portion 24 perforated at 25 to receive the shank 26 of the stud 22. The head is pressed into a transverse undulating contour having a shouldered portion 27 and a seat 28, to receive the head 29 of the stud. 30 Preferably the seat 28 is hexagonally contoured to receive the hexagonal head 29. The head, which is spaced from the seat 28, is

undulated transversely to provide an embossed ridge 30, concentric with axis of transverse semi-circular contour, and preferably axially positioned with regard to the perforation 25, as outlined by the annular face groove 31, disposing arms 32 and 33 to each side of the ridge. The arms 32 and 33 terminate in ears 34 and 35. The ears 34 and 35 may be integral or each constituted of branches 36 and 37 having hook-portions 38 and 39, terminating in edges 40 which may be brought in abutting position and outline a bearing slot 41, in which the edge 42 is sufficiently elongated to transfer the stress or tension of the bearing surfaces 38 and 39 against the wire 18 to the ridge 30, without interference.

It is contemplated by me to bias the ears 34 and 35 from the short side arms 32 and 33 about the ridges 30 as a bearing surface or fulcrum on the trunnion, to achieve resiliency in the frictional fit and contact which the bearing surfaces 38 and 39 make in opposed stressed relation to the ridges 30 upon the trunnion portion of the frame 18.

It will thus be observed that the ears, or trunnion engaging elements 34 and 35 which support the head 23, stress in resilient opposed relationship the grip upon the trunnion portion 18. The frictional grip is exerted independently of the neck 24 from which the stud 22 extends. By independence of the head 23 with relation to the wire 18, the tensioning influence of the finial or other tensioning means upon the collar of the shade will not distort the frictional engagement between the bearing portions of the ears, in opposed relation to the ridges 30.

While I have shown and illustrated in Figures 1 to 5 the crown of the ridge 30 in contact with the trunnion portion 18, I may so intimately press the head 23 into contact with the trunnion portion of the wire 18, assembling the ears therewith, to increase the bearing surface of the ridge to secure various degrees of swiveling action with sufficient frictional contact to support the shade in tilted position. For this purpose, the head 23, when brought into engagement with the trunnion portion 18, is pressed or struck to indent the ridge to form the extended bearing contact 30a, as shown in Figures 6, 7 and 8. Such extended bearing surface 30a may be formed at the time that the head 23 is died out, or when crimping the branches 36, 37, defining the ears 34 and 35, into engagement with the segment 18.

It will be understood that while I have described the ears made of branches 36 and 37 which may be brought into engaging relation with a preformed frame 12 by crimping the branches 36 and 37 about the wire frame, it will be understood that the ears 34 and 35 may be integral members or hooks and the wires of which the frame 12 is made may be guided through the slots 41 formed therein and the frame shaped to outline the branches 16 and 17, after locating the head 23 at the appropriate position, in which event a change in the angularity of the ears 34 and 35 in relation to each other may serve to alter the frictional relationship of the opposed bearing surfaces 38 or 30a to the bearing surfaces 38, 39.

By my construction, in view of the close proximity of the opposed bearing surfaces of the ridge 30 or 30a to the bearing surfaces of the ears, requisite resiliency for frictional swiveling contact is obtainable by relatively inexpensive materials, without requiring the use of tempered

or springy materials to secure the necessary frictional contact.

It will be understood that the inherent benefits of my construction which I enumerate are explanatory and that other inherent advantages will appear to those skilled in the art.

Having thus described my invention and illustrated its use, what I claim as new and desire to secure by Letters Patent is:

1. A lampshade swivel head for supporting a shade stud on a lamp harp comprising a substantially flat disc having a substantially central aperture therethrough for receiving the stud, the area of said disc immediately surrounding said aperture being recessed from one face for receiving the stud head when the stud is inserted through the aperture, an annular ridge formed on said disc outwardly of said recess and projecting from said face, and two ears secured to said disc and depending from said disc face adapted to engage the harp and draw said ridge into frictional engagement with said harp; thereby enabling frictional engagement between the swivel head and the harp by the opposed stressed relationship of the ears and ridge with respect to the harp.
2. A lampshade swivel head as set forth in claim 1, wherein the disc is formed with two oppositely extending lateral arms, and the depending ears are carried by said arms.
3. A lampshade swivel head for supporting a shade stud on a lamp harp comprising a substantially flat disc having a substantially central aperture therethrough adapted to receive the stud, ridged bearing portions projecting from one face of said disc and positioned outwardly of said aperture, forming by their projection a recess therebetween for receiving the stud head when the stud is inserted through the aperture, and two ears secured to said disc and depending from said face adapted to engage the harp and draw said ridged bearing portions into frictional engagement with said harp; thereby enabling frictional engagement between the swivel head and the harp by the opposed stressed relationship of the ears and the ridged bearing portions with respect to the harp.
4. A lampshade swivel head for supporting a shade on a lamp harp comprising a substantially flat disc having a substantially central aperture therethrough, a stud positioned in said aperture, the area of said disc immediately surrounding said aperture being recessed from one face to provide a seat for the stud head, an annular ridge formed on said disc outwardly of said recess and projecting from said face, and two ears secured to said disc and depending from said disc face adapted to engage the harp and draw said ridge into frictional engagement with said harp; thereby enabling frictional engagement between the swivel head and the harp by the opposed stressed relationship of the ears and ridge with respect to the harp.

PHILIP MILLER.
